UNITED STATES PATENT OFFICE.

AUSTIN W. COMSTOCK, OF MOUNT PLEASANT, IOWA.

IMPROVEMENT IN PUNCHING AND SHEARING MACHINES.

Specification forming part of Letters Patent No. **173,530**, dated February 15, 1876; application filed December 18, 1875.

To all whom it may concern:

Be it known that I, AUSTIN W. COMSTOCK, of Mount Pleasant, in the county of Henry and State of Iowa, have invented a new and Improved Cutting and Punching Machine, of which the following is a specification:

In the accompanying drawing, Figure 1 represents a side elevation, Fig. 2 a front view, and Fig. 3 a vertical transverse section on line *cc*, Fig. 1, of my improved cutting and punching machine.

Similar letters of reference indicate corresponding parts.

My invention relates to an improved machine for punching and shearing off flat and round iron, plates, bars, and rods; and it consists of two levers fulcrumed to supporting standards, and provided with front jaws, having punch and die for perforating the plate, which is held by hooks of the lower jaw. The rear ends of the levers have square recesses for shearing off round and flat bars.

In the drawing, A represents a solid supporting frame with side standards, to which the punching and shearing levers are fulcrumed sidewise of each other, so as to swing readily on the fulcrum-rod *a*, passing through perforations of the standards and levers. The levers B are provided with broad front jaws, of which the upper carries the punch *b*, while

to the lower is applied the corresponding die *b'*, with exit perforation. Strong retaining hooks, *d*, are pivoted to the lower jaw and placed with their square parts over the plate-bar, or rod to be punched, so as to retain the same when the punch is withdrawn on opening the levers. The rear or handle parts of the levers B are provided with square recesses, *e*, having cutting edges, *e'*, for the purpose of shearing off flat and round bars with equal facility.

The whole machine combines in compact shape the advantages of a shearing and punching machine that may be readily employed for the different operations.

Having thus described my invention, I claim as new, and desire to secure by Letters Patent—

The improved compound cutting and punching machine, consisting of frame A, having its standards connected by rod *a*, and the levers B, provided at the ends with punch and die *b b'*, the said levers having the corresponding recesses *e*, and cutting edges *e'* near their middle, all as shown and described.

AUSTIN W. COMSTOCK.
